DESIGN FOR A WHEELED TOY

Fred T. Mathews and Charles M. Brauer,
Salt Lake City, Utah

Application February 6, 1945, Serial No. 117,788

Term of patent 7 years

(Cl. D34—15)

To all whom it may concern:

Be it known that we, Fred T. Mathews and Charles M. Brauer, both citizens of the United States, residing in common at 2217 Highland Drive, Salt Lake City, in the county of Salt Lake and State of Utah, have invented a new, original, and ornamental Design for Wheeled Toys, of which the following is a specification, reference being had to the accompanying drawing, forming part thereof.

Fig. 1 is a plan view;

Fig. 2, a front elevation; and
Fig. 3, a side elevation, of a wheeled toy showing our new design.

The pull cord is shown fragmentarily in Figures 1 and 2 for convenience of illustration.
We claim:

The ornamental design for a wheeled toy, as shown and described.

FRED T. MATHEWS.
CHARLES M. BRAUER.
